UNITED STATES PATENT OFFICE.

HENRY HEATH, OF NEW YORK, N. Y., ASSIGNOR TO FISK, CLARK & FLAGG,
OF SAME PLACE.

DESIGN FOR A MADE-UP SCARF.

SPECIFICATION forming part of Design No. 13,325, dated October 3, 1882.

Application filed August 28, 1882. Term of patent 3½ years.

To all whom it may concern:

Be it known that I, HENRY HEATH, a resident of the city, county, and State of New York, have invented and produced a new and original Design for Made-Up Scarfs; and I do hereby declare that the following is a full and exact description thereof, reference being had to the accompanying drawing, and to the letters of reference marked thereon, making a part of this specification.

My design relates to a made-up scarf for men's wear, constructed with crossed aprons, and in which the upper portion of each apron is puffed to relieve the otherwise plain appearance of the scarf.

It consists in imparting to the upper half of the scarf an oblate contour, and in producing in connection therewith a central fold in the center piece of the scarf, extending from the intersection of the aprons outward to the neck-line, folds at the upper edge of each apron overlapping the center piece and extending from the intersection of the aprons diagonally toward the intersection of the neckband with the upper line of the scarf, and lateral folds in the upper outer portion of each apron, which, starting each at the intersection of the ends of the center piece with the neck-line, extend thence downward in a line about parallel with each other and terminate a short distance below the intersection of the aprons each with an outward curve, which is lost in the outer edge of the scarf.

A A are the crossed aprons, B the center piece, and D the neckband, of the scarf. The outer side lines of the aprons, from about the point a on each, at which the side line intersects the edge of the opposite apron, upward to the neck-line, are made parallel to each other, but are curved outwardly, so as to present, in connection with the straight neck-line e e, an oblate outline for the upper section or half, a e e a of the scarf, as shown in the drawing. A central fold bisects the center piece, B, com-

mencing at the point c, at which the aprons intersect over said center piece, and extending nearly to the center of the neck-line at b. The upper edge of each apron is carried from the central intersecting point, e, outward diagonally in a straight line, which terminates at a point, d, on the straight outer-edge line of the center piece a little below its intersection at e with the outline of the scarf, and from said point d a fold extends downward in line about parallel with the center line, b c, if continued, to a point, f, not quite midway the lateral curve a e of the outer edge of the apron, and there curves outward and is lost in said outer edge, substantially as illustrated in the drawing.

I claim as new—

1. The design for a puffed scarf with crossed aprons, consisting of the nearly-parallel curved side lines a e a e, connected by the nearly-straight line, e e, producing substantially an oblate contour in the upper half of the scarf, as herein shown and described.

2. The design for a puffed scarf with crossed aprons, consisting of a central fold, b c, bisecting the center piece of the scarf, straight folds bounding the upper edges of the aprons and extending diagonally each from the point e of their intersection to a point, d, at the outer edge of the center piece, and a lateral fold extending from the intersection at d of the top of each apron with the outer edge of the center piece, downward in a line about parallel with the center fold of the center piece to a point, f, not quite midway the lateral curve of the outer edge of the apron, substantially as herein shown and described.

In testimony whereof I have signed my name to this specification in the presence of two subscribing witnesses.

HENRY HEATH.
